W. H. FORKER.

Brush.

No 67,746.

Patented Aug. 13, 1867.

United States Patent Office.

WILLIAM H. FORKER, OF MEADVILLE, PENNSYLVANIA.

Letters Patent No. 67,745, dated August 13, 1867.

IMPROVED BRUSH.

The Schedule referred to in these Letters Patent and making part of the same.

TO ALL WHOM IT MAY CONCERN:

Be it known that I, WILLIAM H. FORKER, of Meadville city, in the county of Crawford, and State of Pennsylvania, have invented a new and improved Mode of Attaching the Bristles of a Painter's Brush to the Handle thereof; and I do hereby declare that the following is a full and exact description of the same, reference being had to the accompanying drawings, and the letters of reference marked thereon.

Figure 1 represents my invention when it is all put together and the brush completed. A is the handle attached to the head of the brush by a screw, D. B is a hollow conical-shaped head of brass or other suitable metal. C is a "bead" swaged in the head. E is a band of rubber, which may be slipped down towards the point of the bristles F to shorten the brush.

Figure 2 is a sectional view of my invention showing its internal construction. B is the head; G H, a screw riveted at O in handle-socket D, and of course turns with the handle. S S is a cone-shaped cup, with a nut on its bottom at 1, which works on the screw G H. M M is a cylinder of brass, divided into "staves" 4, 5, 6, 7, 8, 9 (see fig. 3) nearly its whole length. 2, 3 is a round band of hard rubber over the end of the cylinder M M, and kept in its place by slightly bending the end of the "staves" out.

This cylinder is placed outside the screw, as shown in fig. 2. The conical cup S S is then screwed on the screw G H a part of the way, and being into the cylinder M M opens the staves in the manner shown in fig. 2, the rubber band stretching as required. The bristles are placed in the head around the cylinder M M. The handle A is now turned, drawing the conical cup S S into the cylinder M M, thus compressing the bristles between the rubber band 2, 3 and the hollow "bead" C, this band and the bead by this means making a "crook" or bend in the bristles, thus preventing them from being drawn out.

What I claim as my invention, and desire to secure by Letters Patent, is as follows, to wit:

I claim the head B, with the hollow "bead" C, in combination with the screw G H, the cylinder M M, and the cup S S, and the rubber band 2, 3, when the same are constructed as described in the aforesaid combination for the purposes set forth.

WM. H. FORKER.
